BAG MANUFACTURE

Irving Gurwick, Mount Vernon, Ohio, assignor
to Shellmar Products Company, Mount Ver-
non, Ohio, a corporation of Delaware

Application May 15, 1936, Serial No. 79,858

3 Claims. (Cl. 93—35)

The present invention relates to containers of the bag type and has particular reference to an improvement in bags and other containers constructed of transparent cellulose sheeting and folded into container form with creases or angular edge portions.

A principal object of the invention is the provision of reinforcing means for the creases or edge portions of transparent cellulose sheeting.

10 An additional object is to provide a bag or similar container which has deposited along the angular edges thereof a reinforcing material composed of a flexible non-fibrous cellulose product or the like.

15 A further object is to provide a method of forming containers having creases or angular edge portions which will not break or shatter as readily as has been the case heretofore.

These and other objects will be evident upon 20 a consideration of the following description of a preferred embodiment of the invention and by reference to the accompanying drawing, in which

25 Fig. 1 is a perspective view, somewhat diagrammatic, of a device for applying an integral reinforcing material to a web of transparent cellulose sheeting;

30 Fig. 2 is a plan view of a satchel bottom bag formed from the web shown in Fig. 1, the bag being shown in collapsed condition; and

35 Fig. 3 is a cross-sectional view taken along line 3—3 of Fig. 2.

In the production of bags and similar types of containers from transparent cellulose sheeting, such as regenerated cellulose and cellulose acetate, it is customary to fold a web of transparent cellulose sheeting into tubular form, to sever bag lengths from the tube, and to fold one end of the tube lengths into closed condition to complete the bag. In such condition the bag is collapsed and 40 the side edges consist of a layer of the transparent cellulose sheeting folded over upon itself and somewhat creased. The bottom of the bag likewise consists of several folded-over portions having creases or angular portions. When containers 45 formed of these materials are used, it has been found that breakage of the containers is most apt to occur along these angular or sharp edges or creases.

In accordance with the present invention, the 50 web of transparent cellulose material from which the containers are formed is provided with one or more longitudinal strips consisting of a deposit of a flexible material of a sufficiently tough nature to reinforce the containers and to reduce the 55 tendency toward breakage. As shown in Fig. 1,

a web 10 is taken from a roll of transparent cellulose sheeting 11 and thereafter passed through an intaglio printing unit. This unit includes an upper impression roll 12 and a lower edge printing cylinder 13 constructed in the usual manner. 5 The lower part of the printing cylinder 13 rotates in a body 14 of the material which it is desired to deposit upon the web as a reinforcing material. The body of material 14 is carried in a bath 15 and the excess material picked up by 10 the roll 13 is scraped therefrom by means of a doctor blade 16. Cylinder 13 is an intaglio copper surfaced cylinder having circular etched portions 17 and 18 for applying a substantially continuous line of the material in the bath 15, it being understood that the doctor blade 16 scrapes the material from the cylinder 13 except along the etched portions 17 and 18.

As a result of passing between the cylinders 12 and 13 the web has deposited thereon longitudinally extending stripes 19 and 20 of the material contained in bath 15.

The material in bath 15 is of the nature of a lacquer ink and includes a heavy bodied nitrocellulose such as "600 second" nitrocellulose. The 25 nitrocellulose is carried in a suitable quick-drying organic solvent which permits the lines of nitrocellulose to be applied and dried quickly before the web is formed into tube lengths. It is characteristic of nitrocellulose of this type that when 30 so deposited it firmly adheres to the regenerated cellulose or cellulose acetate sheeting of which the web 10 is composed and forms a relatively thick body portion of a tough nature which resists shattering of the container along the vulnerable 35 portions covered by the stripes.

After depositing the heavy bodied nitrocellulose stripes, the web is formed into a tube with the stripes 19 and 20 overlapping the edge portions in the manner shown in Fig. 3. That is, the 40 stripes 19 and 20 form a reinforcement for these creased edges that are most likely to be damaged in the use of the bag.

The bag is provided with a satchel bottom as 45 shown in Fig. 2, the portions of the bottom having the stripes 19 and 20 therealong being folded so that the stripes 19 and 20 meet as substantially shown in the drawing. In this way the corners 21 and 22, which are the weakest part of the bottom, are afforded a flexible protection 50 by the stripes 19 and 20, thereby materially increasing the strength of the bag.

As indicated in Fig. 3, the stripes 19 and 20 are printed on the outside surface of the web, but it will be understood that the stripes likewise may 55

be printed on the inside of the web. The invention is applicable to other forms of containers than the specific bag shown in the drawing. In general, it will be possible to apply the invention to any particular form of container or wrapping material by the printing method of the invention. Also, due to the method of application of the stripes 19 and 20 it is possible to apply stripes other than longitudinal stripes to further protect the material. Thus, a transverse stripe may be applied and a fold laid along such stripes. In some cases it will be found desirable to print wider stripes than shown in the drawing. This facilitates the vertical operation, since it is easier to locate the fold along a wider stripe than along a narrow stripe. The material deposited is a heavy bodied nitrocellulose which produces a substantially thicker film per unit of material than in the case of lacquer inks employed in intaglio printing of designs. If desired, the material may be colored to present the appearance of colored stripes on the finished bag or container. Due to the flexibility of the printed stripes and the body of the material the fold lines of the transparent cellulose sheeting are substantially protected thereby. The nitrocellulose stripes are different in their characteristics from the regenerated cellulose and cellulose acetate with which it is desired to employ the material and the combination of the two types of the materials in the manner described materially reduces the shattering tendencies of the containers with which the heavy nitrocellulose is employed. The improved container is produced at a cost which is only slightly in excess of the normal cost of the container and the printed stripes not only are protective but are attractive as well, particularly when colored.

Ordinarily, the transparent cellulose web from

which the containers are constructed will be subjected to a printing operation and wound into the roll form indicated at 11 prior to the operation described hereinabove. That is, the web is subjected to an ordinary printing operation, wound into roll form, unwound, longitudinal lines of the heavy bodied nitrocellulose are applied to the unwound web, and the web then is folded into container form along the lines of the heavy bodied nitrocellulose. Thus, the protective lines of the heavy bodied nitrocellulose are applied just prior to folding the web into bag form.

It will be recognized that the invention as described herein is susceptible to modification without departing from the scope of the appended claims.

I claim:

1. The method of producing containers of transparent cellulose sheeting, which comprises applying longitudinal lines of a quick-drying solution of a heavy bodied nitrocellulose to a traveling web of transparent cellulose sheeting, and folding said web into container form along said lines. 20

2. The process of making containers, which comprises applying a line of 600 second nitrocellulose contained in a solvent to a web of transparent cellulose sheeting, and folding said web into container form along said line. 25

3. The process of producing containers of transparent non-fibrous sheeting, which comprises applying to said sheeting a line of an adherent solution of a relatively heavy bodied cellulose compound contained in a relatively quick-drying solvent, drying said solvent, and folding said sheeting along the line of application of said cellulose compound. 30 35

IRVING GURWICK.
